CLETUS N. ALLERDING, OF MANSFIELD, OHIO, ASSIGNOR TO THE OHIO BRASS COMPANY, OF MANSFIELD, OHIO, A CORPORATION OF NEW JERSEY.

SAND-TRAP.

1,150,480.

Specification of Letters Patent.

Patented Aug. 17, 1915.

Application filed March 2, 1914. Serial No. 821,871.

To all whom it may concern:

Be it known that I, CLETUS N. ALLERDING, a citizen of the United States, residing at Mansfield, in the county of Richland and State of Ohio, have invented certain new and useful Improvements in Sand-Traps, of which the following is a specification.

My invention relates to improvements in sand traps and has more particular reference 10 to improvements in sand traps of the character used in sanding systems in railway trains.

One of the objects of my invention is to provide an improved device of this character which will be simple, durable, and reliable in construction and effective and efficient in operation.

Other objects of my invention will appear hereinafter.

20 Referring to the drawings: Figure 1 is a sectional view on the line 1—1 of Fig. 2 of a structure embodying my invention and showing a sand hopper or supply magazine associated therewith. Fig. 2 is a top plan view of my improved device, and Fig. 3 is an enlarged detail sectional view on the line 25 3—3 of Fig. 1.

My improved structure is intended for use in connection with the so-called air sanding 30 systems wherein the sand is fed into a trap and blown by air passing therethrough down into close proximity to the rails and wheels.

In the structure shown A represents any desired support, such as the floor of the 35 car, and B the hopper or magazine in which the supply of sand is placed. The trap represented generally by C may be positioned in any desirable location either above or below the floor of the car. In the structure 40 shown the hopper B is positioned above the floor of the car and the sand trap secured to the under side of the floor. The sides of the hopper B are slanted or inclined so that the sand will settle down into the 45 trap through an opening in the car floor with which said hopper sides register. The sand trap C is preferably made of a single casting of metal having a flat top or top plate 1 with notches 2 in its side edges for the reception of bolts by which to removably fasten the trap in position so that it will be 50 suspended from the floor of the car.

An annular integral tapered flange 3 rises 55 from the surface of the top plate 1 and fits the opening in the floor of the car beneath

the hopper. This flange and the passage which it forms serves to constitute the sand entrance to the trap. The two side walls 4 of the trap are preferably vertical and parallel and spaced apart. The end wall 5 continues down a short distance almost vertically and in line with the flange 3 and it then makes a turn and assumes a position to form an almost flat inclined portion 6 so that the sand may properly feed down. 60 This inclined wall portion has a comparatively large circular threaded opening which is closed by a removable screw plug 7 so that access may be had to the trap at this point for the purpose of clearing it of any 65 caked or frozen sand, or for any other purpose for which access to the interior of the trap is necessary. This plug has a squared head or end 8 for convenience in removing or replacing. The end wall may then be 70 said to take an upwardly inclined position at substantially right angles to the face of the inclined portion 6 so as to form a baffle wall 9 the function of which will be hereinafter explained. From this baffle portion 75 the wall is made substantially vertical and the trap at this lower portion is preferably 80 given a circular sectional construction which forms a substantially vertical passage 10 serving as a discharge outlet for the trap. 85 The interior 11 of this passage at its lower end is enlarged in diameter and the walls are provided with outstanding and instanding lugs or projections 12, or with any other suitable means for fastening the hose or pipe 90 thereto. This hose or pipe (not shown) is extended down to a point adjacent the rails and wheels and conveys the sand thereto.

In the upper portion of the trap is a wall or partition 13 which begins substantially 95 flush with the flange 3 and inclines diagonally downwardly toward the face of the inclined wall portion 6, and its lower end portion 14 is slightly curved, as shown more clearly in Fig. 1. This partition 13, together with 100 the side walls 4 and the end wall portions 5 and 6 of this structure, form a gradual downwardly narrowing passage for the sand, and the end or lower edge portion 14 of said partition terminates comparatively 105 close to the face of the inclined wall portion 6 so as to leave a rather restricted passage or opening for the sand and prevent flooding or excessive feed thereof. The opposite end wall 15 of the trap structure or casting 110

is flat and disposed substantially vertically, except at its lower end portion 16 which, as shown clearly in Fig. 1, curves around into connection with the bottom wall 17.

In the lower rounded corner portion of the structure, where the end wall 15 and bottom wall 17 merge, there is provided an opening 18 for the reception of the threaded end of an air inlet pipe 19. This pipe leads from any suitable source of air supply under pressure and the supply of air may be controlled by valves or any other desirable means not shown. I prefer to bring the air pipe into the structure at this point because, for obvious mechanical reasons, it is desired, when installing the device, to make the connection here rather than in the side or end walls. Furthermore, by such arrangement in conjunction with the downwardly disposed baffle wall or partition 20, depending from the top plate 1 of the structure, I am enabled to intercept any moisture which may come in with the air and wet the sand. The depending partition 20, in conjunction with the end wall 15 and side walls 4 of the structure, form a chamber 21, and the air coming from the end of the pipe 19 blows directly upward into this chamber. By reason of the relative disposition of the pipe 19 and the walls and baffle wall 20 the air passes upwardly along the wall 15 into the chamber 21, and in order to leave the chamber 21 it must pass downwardly adjacent the baffle wall 20 and around the lower edge of said baffle wall.

It will thus be seen that the air coming into the device under comparatively high pressure and impinging directly against the walls of said chamber, and particularly the baffle plate or wall 20, will deposit on said baffle wall whatever moisture is in the air, and as this moisture accumulates on the baffle wall 20 it will drain down by gravity and drip from the lower edge thereof, and in order to relieve the device of this excess water and moisture I provide a drip opening 22 in the bottom wall 17 substantially below the edge of baffle plate 20. This opening 22 preferably remains open at all times and will drain the water from the device. The curved corner portion 16 also serves to direct any water which accumulates on and drains from the end wall 15, to the drain hole 22. As the air leaves the inlet pipe and enters the chamber 21, which is larger than the pipe it expands to some extent and its pressure decreases, and in order now to direct the air into proper and effective relation to the sand, I provide another partition D of peculiar formation. One portion 23 of this partition wall is disposed vertically and separates the discharge passage or chamber 10 from the air inlet chamber. This partition continues upward therefrom and is given a curved arch-like

formation. This arch-like portion of said partition is disposed adjacent the baffle wall 20, the top plate 3 and the partition wall 13 so as to form a comparatively narrow restricted passage 24 for the air. The arch-like portion of the partition wall D terminates at 25 close to and a little below the baffle wall 13 and its lower end 14 forms a nozzle, so to speak, through which the air emits.

Since the partition 13 and the arch portion of the wall D are substantially parallel the opening 26 of the nozzle is long and narrow and the effect, therefore, is to direct a thin sheet, so to speak, of air against the exposed surface of the sand at this point. In consequence the sand will be bodily blown uniformly from the exposed portion of the supply and carried by the air against the baffle wall 9, which, as is seen in Fig. 1, is disposed adjacent to the end 25 of the arch-like wall and forms therewith a narrow elongated passage communicating with the general discharge passage 10. The sand-laden air, after leaving this narrow passage, is directed to some extent upwardly and into the upper portion of the passage or chamber 10.

It will be noted that the chambers and passages of the device are somewhat larger than the air inlet pipe and that the air after leaving the inlet pipe expands to some extent and its pressure and velocity decreases. These parts are so proportioned that the air upon reaching the nozzle 26 will have such pressure and speed as to properly blow the sand from the supply, but the force of the sand-laden air, after leaving the supply of sand, will not be sufficient to exert a sand-blast action upon the surfaces of the baffle 9 and the arch partition above said baffle. Thus these surfaces will not be eaten or worn away. In fact, when the sand-laden air enters the upper portion of the large passage or chamber 10, the pressure and speed of the air will be practically spent, and since the passage 10 is disposed vertically the sand will fall or settle down therethrough by gravity.

If, for any reason, the discharge passage 10 or any of the parts from thereon should become clogged in any manner the air would be likely to blow back through the body of sand in the chamber and fly about in the car, and to prevent any such disagreeable occurrence I provide a relief means in the chamber 10. In the structure shown I provide for this purpose a small opening 27 in the side wall 4 of the structure, this opening being adjacent the portion 23 of the partition wall D and being open at all times to the outside air. This opening permits the air to escape should the passages and pipes below said opening become clogged, and in the event that said pipes and passages be

come clogged up to the said opening, the excess sand will also escape through said opening. In order, however, to prevent the air and sand from passing through this opening 27 during the normal operation of the device, I provide a short baffle wall 28 over this opening, as shown more clearly in Figs. 1 and 3. This baffle wall 28 guards the opening 27 and the sand and air pass on downward instead of through the opening 27.

It will be obvious to those skilled in the art, after having obtained an understanding of my invention from the disclosures herein made, that the structure shown and described may be considerably modified without departing from the principles or the scope of my invention and I wish it to be so understood.

20 What I claim is:

1. In a device of the class described, the combination of a casing forming a chamber having a discharge outlet, a sand-feeding chamber having communication with said outlet for exposing a portion of the sand adjacent the outlet, means restricting the flow of the sand, and means for directing a stream of air against the surface of the exposed portion of the sand to blow the surface sand away from the exposed portion.

25 2. In a device of the class described, the combination of a casing forming a chamber having a discharge outlet, a sand-feeding chamber having communication with said outlet, means restricting the flow of the sand, means for directing a stream of air against the exposed portion of the sand, and a baffle for diverting the sand-laden air toward the upper portion of said outlet in the 40 direction from which the air comes.

30 3. In a sand trap of the class described, the combination of a casing having a discharge chamber and an outlet therefor, means for reversing and directing a current of air into the upper portion of said chamber, and means forming a sand-holding chamber having a portion exposed to the current of air.

35 4. In a sand trap of the class described, the combination of a casing having a discharge chamber and an outlet therefor, means for directing a current of air into the upper portion of said chamber, means for forming a sand-holding chamber having an opening exposed to the current of air, means forming an air chamber in said casing, and a baffle therein against which the current of air impinges for collecting the moisture from the air.

40 5. The combination of a casing having a sand inlet and a discharge chamber having an outlet, means forming a sand chamber having an opening through which the sand feeds, means for directing the current of air against the sand exposed at said open-

ing, and a baffle for diverting and reversing a current of sand-laden air from the opening into the upper portion of said discharge chamber.

6. The combination of a casing having a sand inlet and a discharge chamber having an outlet, means forming a sand chamber having an opening through which the sand feeds, means for directing the current of air against the sand exposed at said opening, a baffle for diverting a current of sand-laden air into the upper portion of said discharge chamber, and a relief vent in the wall of said discharge chamber.

7. In a sand trap of the class described, the combination of a casing having a sand-holding chamber, a discharge chamber having an outlet, said sand chamber having an opening at its lower end through which the sand is exposed to the discharge chamber, means forming a nozzle for directing a current of air against the surface of the exposed sand at said opening for blowing the surface sand out of the opening, and means for directing and diverting the sand-laden air from the opening into said discharge chamber.

8. In a device of the class described, the combination of a casing having a sand-holding chamber, said chamber having an opening through which the sand is exposed, and a partition in said casing dividing said casing into an air chamber and a discharge chamber, and having a portion thereof disposed adjacent one wall of said sand chamber and adjacent said opening to form a nozzle for directing the air against the exposed sand, a baffle wall forming a discharge from said nozzle to said discharge chamber and against which the sand-laden air is impinged.

9. In a device of the class described, the combination of a casing having a sand-holding chamber, said chamber having an opening through which the sand is exposed, a partition in said casing dividing said casing into an air chamber and a discharge chamber, and having a portion thereof disposed adjacent one wall of said sand chamber and adjacent said opening to form a nozzle for directing the air against the exposed sand, a baffle wall forming a discharge from said nozzle to said discharge chamber and against which the sand-laden air is impinged, an air inlet for said air chamber, and means in said air chamber for collecting the moisture from the incoming air.

10. In a device of the class described, the combination with a casing having a sand chamber and sand discharging means, and having an air chamber, an air inlet for said chamber, and means in said chamber for collecting the moisture from the incoming air.

11. In a device of the class described, the combination with a casing having a sand

chamber and sand discharging means, and having an air chamber, an air inlet for said chamber, a baffle in said air chamber against which the incoming air impinges for extracting the moisture therefrom, and means for draining the moisture from said air chamber as it drips from said baffle.

12. The combination of a sand trap having a discharge chamber into which the sand-laden air is blown, said discharge chamber having a main outlet and an auxiliary relief opening for relieving the pressure when the flow of sand from said outlet becomes clogged.

15 13. In a device of the class described, the combination of a casing having a sand holding chamber with a communicating feed chamber open to discharge, and means for directing a stream of air against the surface 20 of the sand in the feeding chamber to carry the sand in a direction reverse to the initial direction of movement of the air in the feed chamber.

14. In a device of the class described, the 25 combination with a containing casing hav-

ing a gravity feeding chamber with a lateral discharge opening above the bottom, and means for directing a blast of air from above the opening against sand in the feeding chamber to discharge the sand from the 30 opening in a reverse parallel direction.

15. In a device of the class described, the combination with a containing casing having a gravity feeding chamber with a lateral discharge opening above the bottom, and 35 means for directing a blast of air against sand in the bottom of the feeding chamber to lift it therefrom and discharge the sand in a reverse direction out of the opening and parallel with the direction of the incoming 40 air.

In testimony whereof I have signed my name to this specification, in the presence of two subscribing witnesses, on this 25 day of February A. D. 1914.

CLETUS N. ALLERDING.
